His Attorney

UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed January 3, 1930. Serial No. 418,218.

My invention relates to railway traffic controlling apparatus, and particularly to apparatus for manually controlling a railway signal.

One feature of my invention is the provision of means controlled by a signal and by traffic conditions for releasing the approach locking of a control lever for the signal after the lapse of a measured period of time.

10 I will describe one form of apparatus embodying my invention, and will then point out the novel features thereof in claims.

The accompanying drawing is a diagrammatic view illustrating one form of apparatus embodying my invention.

Referring to the drawing, the reference characters 1 and 1^a designate the track rails of a stretch of railway track which is provided with a switch F. This stretch of track is divided by insulated joints 2 into sections A—B and B—C. Section A—B will be referred to hereinafter as an approach section, and section B—C, in which switch F is located, will be referred to as a detector section. Each of these sections is provided with a track circuit which includes a battery 3 connected across the rails adjacent one end of the section, and a relay 4 designated by the reference character R with a distinguishing exponent and connected across the rails adjacent the opposite end of the section.

A signal designated by the reference character S¹ governs eastbound traffic, that is, traffic moving toward the right as shown in the drawing, and signals S² and S³ govern westbound traffic. Signal S¹ operates a contact 5 which is closed when and only when signal S¹ indicates "stop." As here shown, signals S are of the semaphore type, although my invention is not limited to this form.

Signals S are controlled by a manually operable lever V of an interlocking machine.

45 Another manually operable lever in the same machine, not shown in the drawing, controls switch F. Lever V has a normal position n, a control position to the left m, and a control position to the right r, as well as an indication position to the left b, and an indication position to the right d. Lever V and the lever which controls switch F are so interlocked mechanically that the lever for switch F can not be moved to cause the operation of switch F unless lever V is in

its n position. Approach locking of switch F is therefore accomplished by providing approach locking for lever V so that lever V can not be returned to its n position.

The return of lever V to its n position is controlled by an electric lever lock designated by the reference character L. Lock L comprises a control winding 23, a segment 22, and a locking dog 20 which is controlled by winding 23. Segment 22 is provided with a lug 21. When lever V is moved to its r position for clearing signal S¹, segment 22 is moved toward the left. If, now, winding 23 is de-energized, dog 20 will rest on segment 22. If winding 23 is still de-energized when lever V is moved back toward its n position, dog 20 will engage lug 21 when lever V reaches its indication position d, thus preventing the completion of the return of lever V to its n position. If, now, winding 23 becomes energized, dog 20 will be lifted out of engagement with lug 21 and will so permit the movement of lever V to be continued to the n position.

50 Lever V operates a contact 4 which is closed when lever V occupies its r position only, a contact 15 which is closed when lever V occupies its r or its d or any intermediate position, and a contact 17 which is closed when lever V occupies its d position only.

A time element device H, here shown as a thermal relay, but which may be of any other suitable type, is controlled by contact 5 of signal S¹ and by a back contact of relay R¹ when lever V is moved to its d position. Relay H, as here shown, comprises a control element 19 and a contact 12 which becomes closed when and only when control element 19 has been energized for a measured period of time.

55 As shown in the drawing, all parts are in their normal condition, that is, sections A—B and B—C are unoccupied, lever V is in its n position, and signals S are indicating "stop".

I will now assume that the leverman desires to clear signal S¹ for an eastbound train to move over switch F in its normal position as shown in the drawing. He therefore moves lever V to its r position, completing a circuit passing from terminal x of a source of current not shown in the drawing, through contact 4 of lever V, and the mechanism of signal S¹ to terminal o of the same source of current. The arm of

signal S^1 will then move to its "proceed" position.

If, before a train enters section A—B, the leverman desires to return lever V to its n position to permit him to reverse switch F,

- 5 he will return the arm of signal S^1 to its "stop" position by moving lever V back as far as its "indication" position d . When lever V has left its r position, the circuit for 10 signal S^1 , as already traced, is opened at contact 4 of lever V. The arm of signal S^1 then returns to its "stop" position, completing at its contact 5 a circuit for winding 23 of lock L passing from terminal x , through 15 contact 5 of signal S^1 , contact 6 of relay R^1 , wires 7 and 14, contact 15 of lever V, and winding 23 of lock L to terminal o . Winding 23, being thus energized, lifts dog 20 out of engagement with lug 21, and the 20 leverman will then complete the movement of lever V to its n position.

I will next assume that, with all parts again in their normal condition, the leverman again clears signal S^1 by moving lever 25 V to its r position as previously described. I will also assume that an eastbound train moves through section A—B and enters section B—C.

- In order to return lever V to its n position while the train is in section B—C, the leverman will move lever V as far as its d position, causing the arm of signal S^1 to be returned to the "stop" position. A second circuit is then completed for winding 23 of 35 lock L passing from terminal x , through contact 5 of signal S^1 , wires 8 and 9, contact 10 of relay R^2 , wire 14, contact 15 of lever V, and winding 23 of lock L to terminal o . Winding 23 being thus energized, 40 dog 20 is lifted out of engagement with lug 21, and the leverman then completes the movement of lever V to its n position.

I will now assume that, with all parts again in their normal condition, the leverman again clears signal S^1 by moving lever 45 V to its r position. I will also assume that a train then enters section A—B, and that the leverman then desires to change the position of switch F. He therefore starts the 50 return of lever V to its n position by moving lever V to its d position, at which further movement of lever V is checked by engagement of dog 20 with lug 21. The arm of signal S^1 moves to its "stop" position, 55 completing a circuit for control element 19 of thermal relay H passing from terminal x , through contact 5 of signal S^1 , wires 8, 9 and 16, contact 17 of lever V, contact 18 of relay R^1 , and control element 19 of relay H to terminal o . After the lapse of a measured period of time, contact 12 of relay H closes, completing a third circuit for winding 23 of lock L passing from terminal x , through contact 5 of signal S^1 , wires 8 and 60 11, contact 12 of relay H, wires 13 and 14,

contact 15 of lever V, and winding 23 of lock L to terminal o . Winding 23 now lifts dog 20 out of engagement with lug 21, and the leverman then continues the movement of lever V to its n position.

70 Lever V, when moved to its m position, controls signal S^2 or signal S^3 according as switch F is in its normal or its reverse position. Lock L is controlled by signals S^2 and S^3 similarly to the manner in which it 75 is controlled by signal S^1 as already described. The circuits by which lock L is controlled by signals S^2 and S^3 are, therefore, omitted from the drawing.

80 From the foregoing description and the accompanying drawing, it is clear that with apparatus embodying my invention, when lever V is in its r position and an eastbound train is in approach section A—B but section B—C is unoccupied, if the leverman 85 desires to change the position of switch F, he will move lever V to its d position, and then, after the lapse of a measured period of time, winding 23 of lock L will become 90 energized through contact 12 of time element device H, thus permitting the final movement of lever V to its n position without any further manual releasing operation.

95 Although I have herein shown and described only one form of railway traffic controlling apparatus embodying my invention, it is understood that various changes and modifications may be made therein within the scope of the appended claims without departing from the spirit and scope of my 100 invention.

Having thus described my invention, what I claim is:

1. In combination, a manually operable lever, a railway traffic governing device controlled by said manually operable lever, and means controlled by said traffic governing device for preventing operation of said manually operable lever for a measured period of time after response of the device to an 105 operation of the lever.

2. In combination, a manually operable lever, a railway traffic governing device controlled by said manually operable lever, a time element device controlled by said traffic governing device and set into operation when said device completes a movement in response to an operation of said lever, and means controlled by said time element device for controlling said manually operable 110 lever.

115 3. In combination, a manually operable lever, a railway traffic governing device controlled by said manually operable lever, means controlled by said traffic governing device for preventing operation of said manually operable lever, and means controlled by traffic conditions for permitting such operation of said manually operable lever after the lapse of a measured period of time.

4. In combination, a manually operable lever, a railway traffic governing device controlled by said manually operable lever, means controlled by traffic conditions for preventing operation of said manually operable lever, and means controlled by said traffic governing device for permitting such operation of said manually operable lever after the lapse of a measured period of time. 70
5. In combination, a manually operable lever having a first and a second position, a railway signal, means controlled by said lever when in said second position for causing said signal to indicate "proceed", and means controlled by said signal for at times preventing movement of said lever from said second to said first position for a measured period of time. 75
6. In combination, a manually operable lever having a first and a second position, a railway signal, means controlled by said lever when in said second position for causing said signal to indicate "proceed", an electric lock which when de-energized prevents movement of said lever from said second to said first position, and means controlled by said signal for energizing said lock after the lapse of a measured period of time. 80
7. In combination, a stretch of railway track, a signal for said stretch, an approach track section for said signal, a track circuit for said section including a track relay, a manually operable lever having a normal and a reverse and an indication position, means controlled by said lever when in said reverse position for causing said signal to indicate "proceed", a lever lock which permits movement of said lever from its reverse to its indication position but which when deenergized prevents movement of said lever past said indication position toward said normal position, a time element device controlled by a back contact of said track relay, and means controlled by said time element device for energizing said lever lock when said time element device has been energized a measured period of time. 85
8. In combination, a railway signal, a manually operable lever having a normal and a reverse position, means controlled by said lever when in said reverse position for causing said signal to indicate "proceed", a lever lock which when de-energized prevents movement of said lever from said reverse to said normal position, a time element device controlled by said signal, and means controlled by said time element device for energizing said lever lock upon the lapse of a measured period of time after the arm of said signal has been restored to the normal position. 90
9. In combination, a stretch of railway track, a signal for said stretch, a contact controlled by said signal and which is closed when and only when said signal indicates stop, an approach track section for said signal, a track circuit for said section including a track relay, a manually operable lever having a normal and a reverse position, means controlled by said lever when in its said reverse position for causing said signal to indicate "proceed", a lever lock which when de-energized prevents movement of said lever to its said normal position, a circuit for said lever lock including said signal-controlled contact and a front contact of said track relay as well as a source of current and said lever lock in series, a time element device, a control circuit for said time element device including said signal-controlled contact and a back contact of said track relay as well as a source of current and said time element device in series, and means controlled by said time element device for completing a branch path around said relay contact in said lever lock circuit when said time element device has been energized a measured period of time. 95
10. In combination, a main section and an approach section of railway track, a manually operable lever having a first and a second position, a signal for governing traffic through said main section and arranged to indicate "proceed" when said lever occupies said second position, and means operating when said approach section is occupied for limiting the motion of said lever for a measured interval of time after said lever is moved toward said first position from said second position. 100
11. In combination, a main section and an approach section of railway track, a manually operable lever having a first and a second position, a signal for governing traffic through said main section and arranged to indicate "proceed" when said lever occupies said second position, time measuring means set into operation when said lever is moved from said second position toward said first position while said approach section is occupied, and means controlled by said time measuring means for at times limiting the movement of said lever. 105
12. In combination, a main section and an approach section of railway track, a manually operable lever having a first and a second position, a signal for governing traffic through said main section and arranged to indicate "proceed" when said lever occupies said second position, means actuated when said lever is moved from said second position toward said first position while said approach section is occupied and requiring a measured interval of time to complete its operation, and means for limiting movement of said lever during said interval of time. 110
13. In combination, a main section and an approach section of railway track, a manually operable lever having a first and a second position, a signal for governing traffic through said main section and arranged to indicate "proceed" when said lever occupies said second position, means actuated when said lever is moved from said second position toward said first position while said approach section is occupied and requiring a measured interval of time to complete its operation, and means for limiting movement of said lever during said interval of time. 115
14. In combination, a main section and an approach section of railway track, a manually operable lever having a first and a second position, a signal for governing traffic through said main section and arranged to indicate "proceed" when said lever occupies said second position, means actuated when said lever is moved from said second position toward said first position while said approach section is occupied and requiring a measured interval of time to complete its operation, and means for limiting movement of said lever during said interval of time. 120
15. In combination, a main section and an approach section of railway track, a manually operable lever having a first and a second position, a signal for governing traffic through said main section and arranged to indicate "proceed" when said lever occupies said second position, means actuated when said lever is moved from said second position toward said first position while said approach section is occupied and requiring a measured interval of time to complete its operation, and means for limiting movement of said lever during said interval of time. 125
